UNITED STATES PATENT OFFICE.

CALVIN A. RICHARDSON, OF WATERVILLE, MAINE.

INSTRUMENT FOR STIRRING STRAW AND HUSK BEDS.

Specification of Letters Patent No. 14,574, dated April 1, 1856.

To all whom it may concern:

Be it known that I, CALVIN ASA RICHARDSON, of Waterville, in the county of Kennebec, in the State of Maine, have invented a new and Improved Mode of Constructing an Instrument for the Purpose of Stirring Straw, Husks, and other Filling in Beds; and I do hereby declare that the following is a full and exact description thereof.

10 The nature of my invention consists, in a handle, or staff, A, two feet more or less in length, with two or more hooks or irons, B, C, made fast to the end or ends of said staff, as shown at, B, C, in the accompanying drawings. Said irons are made crooked, with a blunt point or ball on the ends, as

shown in said drawings; also, said irons or hooks, when made fast to the staff, should be made fast to the reverse of each other, as one is to draw the straw or filling, and the other 20 to shove with. When two irons are made fast to one end they should be set quartering more or less as required.

What I claim as my invention, and desire to secure by Letters Patent is—

25 The mode of constructing said instrument for the purpose of stirring filling in beds.

CALVIN ASA RICHARDSON. [L. S.]
